REMOVABLE TAPE ROLL HOLDER FOR
PRINTING MACHINES

Alfred Edward Thompson, Croydon, England, assignor to Creed and Company Limited, Croydon, England, a British company

Application May 5, 1945, Serial No. 592,171
In Great Britain April 4, 1944

Section 1, Public Law 690, August 8, 1946
Patent expires April 4, 1964

10 Claims. (Cl. 197—133)

1

This invention relates to teleprinters and more particularly to the means for holding a continuous roll of paper tape on which printing is to be effected.

An object of the invention is to provide a tape teleprinter in which the paper tape can be readily replenished.

According to one feature of the invention we provide a combined keyboard transmitter and a receiving tape teleprinter in which a tape roll holder is mounted at the rear of the machine on a supporting member and is readily removable from and replaceable in position.

According to another feature of the invention a tape teleprinter comprises a supporting base, a horizontal rail fixed to said base and extending along one edge thereof, a tape roll holder and a supporting member for a tape roll holder mounted on said rail, so as to be slidable into and out of operative position.

The horizontal rail also serves to protect the instrument against damage during transport on maintenance trolleys.

One embodiment of the invention is hereinafter described with reference to the accompanying drawings in which:

Fig. 1 is a rear view of a tape teleprinter with the cover in position, and with a tape roll holder supported exteriorly of the cover.

Fig. 2 is a view similar to Fig. 1 but showing the supporting member for the tape roll holder removed from its position and with a portion of the guide rail cut away.

Referring to the drawings, these are rear views of a combined keyboard transmitter and a tape teleprinter receiver with a cover 1 in place over the latter. The keyboard is at the front of the machine and is accordingly not shown in the drawings. Fixed to the rear of the supporting base of the machine is an angle member 2 formed with an upturned edge 3. This member 2 constitutes a horizontal rail. A quadrantal piece 4 is fastened to the rail 2, serving as a strut therefor, and has a turned-up edge within the edge 3. Within the groove formed by this turned-up edge there is formed in piece 4 a struck-up tongue 5. Fixed to the vertical portion of the angle member 2 is a vertical support 6 having a short horizontal portion 7 fixed to the upper end thereof.

The tape roll holder 8 is journaled in a supporting plate 9 and held thereto by a spring finger 10. The supporting plate 9 with the tape roll holder 8 in position thereon can be pushed into the position shown in Fig. 1 with its lower edge sliding within the upturned edge 3 and the

turned-up edge of the quadrantal piece 4, a notch 11 in the lower edge sliding over the upturned tongue 5 which serves to hold the plate 9 in operative position. A channel member 12 fixed to the rear of plate 9 slides over the horizontal portion 7 and serves to guide the plate 9 into position. The left hand edge of plate 9, as seen in Fig. 2 fits into a guide member 13. The plate 9 when in position in the rear of the machine is inclined to the vertical as shown and remains in this operative position whether or not the cover 1 of the teleprinter is in position.

Associated with the horizontal rail 2 and fastened to the instrument base is a vertical rail 14 which provides a rigid support if the instrument is turned up on its end for access to components and wiring underneath the base. The guide member 13 above referred to is fixed to this vertical rail 14.

As the plate member 4 does not occupy the full extent of the rear of the machine the unoccupied section contained by the horizontal rail 2 and vertical rail 14 is provided with side members 15 to form a receptacle for messages, such as finished traffic awaiting collection for filing.

The paper tape 16 as it leaves the tape roll holder 8 passes between guide rollers 17 and thence over a horizontal roller journaled in a portion 18 of a lever 19 pivoted on the axis of the upper guide roller 17. The lever 19 carries a block 20 and a spring 21 urges the lever 19 in a clockwise direction to hold the block 20 against the rim of the tape roll holder 8. The paper tape than passes vertically upwards and over a horizontal roller 22 and thence passes between gripping member 23 to a paper feeding mechanism described in the copending application of R. D. Salmon, bearing Serial No. 589,247 and filed April 19, 1945, which application has matured into Patent No. 2,480,165, dated August 30, 1949. This paper feeding mechanism is mounted on a frame 24 which fits in an aperture in the cover 1, the paper feeding mechanism, a paper feed alarm mechanism and an ink ribbon feeding and reversing mechanism being mounted in the interior of the frame 24, whilst the printing platen is mounted on the exterior of said frame as described in the above-mentioned application. The block 20 pressing against the rim of the tape roll holder 8 acts as a brake to maintain a slight tension in the paper and to prevent excessive unwinding of the paper tape when suddenly pulled. A pull on the tape moves the lever 19 in a counterclockwise direction against spring 21 and thus removes block 20 from the rim of the holder 8 allowing the

latter to rotate, but as soon as the pull ceases the spring 21 pulls the lever 19 in a clockwise direction and applies block 20 to the rim of the holder 8 to check its rotation.

It will be seen that the operator can remove and replace the plate 9 whilst seated in front of the keyboard. A new roll of tape can be fitted in the holder and the tape threaded past the printing platen, without opening the cover. With the roll holder lying flat on the table, there is no danger of the outer layers of tape falling off the roll before the plate 9 is put back into position and the threading of the tape to the printing point is greatly facilitated. In order to guard against damage to the tape whilst the plate 9 is being withdrawn and replaced, one edge of the plate 9 is bent over to form a guard 25 and a further guard member 26 is fixed to the plate. The fingers of the operator grasp guard members 25 and 26 during withdrawal and replacement of the plate 9.

What is claimed is:

1. In a machine for printing on a continuously fed tape, said machine having an exterior rail, a plate slidably supported on said exterior rail, tape carrying means rotatably mounted on said plate, and means for continuously feeding said tape into printing position.

2. In a machine for printing on a continuously fed tape, said machine having an exterior rail, a plate slidably supported on said exterior rail, tape carrying means rotatably mounted on said plate, said plate further including a guard member facilitating removal of said plate from said rail, for receipt of a new tape supply, and means for continuously feeding said tape into printing position.

3. In a machine for printing on a continuously fed tape, said machine having an exterior rail, a plate slidably supported on said exterior rail, tape carrying means rotatably mounted on said plate, means for continuously feeding said tape into printing position, said plate further including brake mechanism engageable with said tape carrying means to oppose feeding of said tape, and means for disengaging said brake mechanism from said tape carrying means.

4. In a machine for printing on a continuously fed tape, said machine having an exterior rail, a plate slidably supported on said exterior rail, tape carrying means rotatably mounted on said plate, means for continuously feeding said tape into printing position, said plate further including brake mechanism engageable with said tape carrying means to oppose feeding of said tape, and means for disengaging said brake mechanism from said tape carrying means, said last-named means including a lever pivotally mounted on said plate, and shiftable by pull exerted on said tape by said tape feeding means.

5. In a machine for printing on a continuously fed tape, said machine having an exterior rail, a plate slidably supported on said exterior rail, tape carrying means rotatably mounted on said plate, and means cooperating with said rail to support said tape carrying means and plate during tilting of the machine for inspection of the underside thereof.

6. In a machine for printing on a continuously fed tape, said machine having an exterior rail, a plate slidably supported on said exterior rail, tape

carrying means rotatably mounted on said plate, and means cooperating with said rail to support said tape carrying means and plate during tilting of the machine for inspection of the underside thereof, said last-named means comprising a second exterior rail adjacent said first-named rail and in angular relation thereto and a guide member attached to said second exterior rail, said guide member adapted to engage a portion of said plate.

7. In a machine for printing on a continuously fed tape, said machine having an exterior rail, a plate slidably supported on said exterior rail, tape carrying means rotatably mounted on said plate, and means co-operating with said rail to support said tape carrying means and plate during tilting of the machine for inspection of the underside thereof, said last-named means comprising a message receiving compartment adjacent said first-named rail and in angular relation thereto and a guide member attached to said compartment, said guide member adapted to engage a portion of said plate.

8. In a machine for printing on a continuously fed tape, said machine having an exterior rail, a plate slidably supported on said exterior rail, tape carrying means rotatably mounted on said plate, and means co-operating with said rail to support said tape carrying means and plate during tilting of the machine for inspection of the underside thereof, said last-named means comprising a second exterior rail adjacent said first-named rail, and in angular relation thereto, and means extending from each of said rails to yieldably retain said plate in tape-feeding position.

9. In a printing machine having an externally mounted tape wheel, means for resisting rotation of said wheel, tape feed means responsive to the printing operation for causing rotation of said wheel notwithstanding said resisting means and a removable slide-plate supporting said wheel and resisting means.

10. Supporting means for a roll of tape adapted to be fed to a printing machine, said supporting means comprising a rail attached to the exterior of said machine, a plate slidably supported on said rail, tape carrying means rotatably mounted on said plate, and means cooperating with said rail to support said tape carrying means and plate during tilting thereof from the normal disposition.

ALFRED EDWARD THOMPSON.
